W. P. MURPHY

CAR ROOF

Original Filed Jan. 10, 1921

Walter P. Murphy, Inventor:
by Compton

His Attorneys

UNITED STATES PATENT OFFICE.

WALTER P. MURPHY, OF NEW YORK, N. Y., ASSIGNOR TO P. H. MURPHY COMPANY, OF NEW KENSINGTON, PENNSYLVANIA, A CORPORATION OF PENNSYLVANIA.

CAR ROOF.

Original application filed January 10, 1921, Serial No. 436,170. Divided and this application filed September 4, 1923. Serial No. 660,813.

To all whom it may concern:

Be it known that I, WALTER P. MURPHY, a citizen of the United States, and a resident of the city of New York, in the county of 5 New York and State of New York, have invented a new and useful Improvement in Car Roofs, of which the following is a specification.

This invention relates principally to eaves 10 constructions for heavy gage steel car roofs and is a division of my pending application for patent for improvement in car roofs, Serial No. 436,170, filed January 10, 1921.

The principal objects of the present invention are to obtain a waterproof eaves 15 construction, to protect the bolts that secure the roof to the substructure of the car, to stiffen the eaves ends of the roof, to locate the securing rivets for the eaves ends of the 20 sheet outside of the car and to enable the roof to be applied to the car as a unitary structure. Other objects are simplicity, strength, durability, and tightness.

The invention consists principally in the 25 means hereinafter set forth for securing heavy gage steel roofs to cars having wood construction; and it also consists in the parts and arrangements hereinafter described and claimed.

30 The accompanying drawing which forms part of this specification is a vertical cross-section through the eaves portion of a car roof embodying my invention.

The present roof comprises rigid load sustaining roof sheets 3 of heavy gage steel, arranged cross-wise of the car and preferably extending from eaves to eaves thereof. The side margins of adjacent sheets are turned up at right angles forming side 35 flanges 4, which extend from end to end of the roof sheets and merge into the plane of the body of the sheets at said ends. Pressed sheet metal seam covers 5 of inverted U-shape in cross section embrace the side 40 flanges 4 of adjacent sheets, and said seam covers and said flanges are fastened together by horizontal rivets 5^a. The seam covers 5 are provided with lateral base flanges 6 and have downwardly curved eaves end portions 45 that merge into the plane of said base flanges at the eaves ends of said seam covers. The eaves ends of the roof sheets 3 overhang the side plates 7 of the car and are turned down,

as at 8; and the eaves ends of the seam covers are turned down, as at 9, over the depending 55 eaves flanges 8 of said roof sheets. The upper edge of the side sheathing boards 10 terminate below the top of the side plate and are nailed or otherwise secured to the outer 60 face thereof.

The overhanging eaves ends of the roof sheets are riveted to the outwardly turned lateral top flange of an eaves angle strip 15; and the other or vertical flange of said angle strip is secured to the outer face of the side 65 plates above the upper edge of the side sheathing 10, by the bolts 17.

A sheet metal flashing strip 16 is secured to the under side of the outwardly extending flange of the eaves angle 15 by the rivets 70 12 which secure the eaves end of the roof sheets thereto. This flashing is extended downwardly and outwardly at an angle across the head of the securing bolt 17 and thence downwardly over the outer surface 75 of the side sheathing 10 for a suitable distance. This flashing strip protects the heads of the securing bolts 17, thus preventing water from following the bolt and reaching the interior of the car, and also covers the 80 upper edge of the siding and prevents water from entering between the side plate and said siding.

The flashing strip 16 not only prevents water from reaching the interior of the car 85 between the side plate and the side sheathing, but also protects the head of the securing bolt 17 and prevents water from following the bolt and reaching the interior of the car.

Another important advantage of the hereinbefore described construction is that the roof sheets can be assembled and riveted to the connecting angle off the car before the same are applied thereto; that is, the whole 95 roof may be assembled off the car and applied to the car as a unitary construction. When it is desired to remove a damaged sheet, the rivets securing said sheets to said angles can be sheared, as the eaves construction allows ample room for cutting and re-driving these rivets. If desired, the nuts 100 can be placed on the outside of the eaves of the side plate thereby permitting the removal of the eaves angle from the outside 105 of the car, although, in actual practice, it is

preferable to have the nuts on the inside for the sake of inspection and to enable the nuts to be tightened without removing the fascia.

5 What I claim is:

1. An eaves construction for car roofs comprising a side plate, metallic roofing extending outwardly beyond the outer face of said side plate, side sheathing secured to the 10 outer face of said side plate, with its upper edge terminating below the upper surface of said side plate, an angle having one flange secured to the outer face of said side plate above said side sheathing and having its 15 other flange projecting therefrom and secured to the under side of said roofing, and a flashing strip secured to said eaves angle and covering the upper edge of said side sheathing.
- 20 2. An eaves construction for car roofs comprising a side plate, metallic roofing extending outwardly beyond the outer face of said side plate, side sheathing secured to the outer face of said side plate with its 25 upper edge terminating below the upper surface of said side plate, an angle having one flange secured to the outer face of said side plate above said side sheathing and hav-

ing its other flange projecting therefrom and secured to the upper side of said roofing, and a flashing strip secured to the under side of said last mentioned flange of said angle, said flashing strip extending downward across the securing means for said angle and over the upper edge of said side 30 sheathing.

3. An eaves construction for car roofs comprising a side plate, metallic roofing extending outwardly beyond the outer face of said side plate, an angle having one flange 35 secured to the outer face of said side plate and having its other flange projecting therefrom and secured to the under side of said roofing, the eaves end of said roofing being turned down beyond the outer edge of the 40 outwardly projecting flange of said angle, side sheathing secured to the outer face of said side plate, with its upper edge terminating below the upper surface of said side plate, and a flashing strip secured to 45 said eaves angle and covering the upper edge of said side sheathing.

Signed at Chicago, Ill., this 31st day of August, 1923.

WALTER P. MURPHY.
